F. HEATH.
HOLLOW WALL CONSTRUCTION.
APPLICATION FILED SEPT. 23, 1916.

1,391,318.

Patented Sept. 20, 1921.

UNITED STATES PATENT OFFICE.

FREDERICK HEATH, OF TACOMA, WASHINGTON, ASSIGNOR TO HEATH UNIT TILE COMPANY, OF TACOMA, WASHINGTON, A CORPORATION OF WASHINGTON.

HOLLOW-WALL CONSTRUCTION.

1,391,318.

Specification of Letters Patent. Patented Sept. 20, 1921.

Application filed September 23, 1916. Serial No. 121,760.

To all whom it may concern:

Be it known that I, FREDERICK HEATH, a citizen of the United States, and a resident of Tacoma, in the county of Pierce and State 5 of Washington, have invented a certain new and useful Improvement in Hollow-Wall Construction, of which the following is a specification.

My invention relates to improvements in 10 hollow wall constructions, and it consists in the arrangements herein described and claimed.

An object of the invention is to provide a wall construction in which hollow blocks 15 may be laid horizontally without exposing the voids in the blocks. To this end, I make use of mitered blocks at the corners which alternate with blocks disposed vertically, the construction being such that the voids are 20 not only hidden, but the courses are locked together.

A further object of my invention is to provide a mitered hollow block.

Other objects and advantages will appear 25 in the following specification, and the novel features of the invention will be particularly pointed out in the appended claims.

My invention is illustrated in the accompanying drawing forming a part of this application in which:

Figure 1 is a perspective view showing a twelve inch wall constructed according to my invention, the upper courses being separated to illustrate the construction;

Fig. 2 is an enlarged detail horizontal sectional view through one of the courses having the mitered blocks;

Fig. 3 is a perspective view of a pier or column, and

Fig. 4 is a sectional view through a portion of a window jamb construction.

In carrying out my invention, I make use of mitered hollow blocks. These blocks may have one or more voids. In Fig. 1 I have 45 shown a block A, having three voids, but it will be understood that the invention is not confined to a block having any particular number of voids.

As will be seen from Fig. 2, the block B is 50 cut along the line *b*, while the companion block C is cut along the line *c*. In Fig. 4 the block D is cut along the line *d*, while the block E is cut along the line *e*. The construction described permits the making of a

corner by fitting the blocks together in such 55 manner as to hide the voids.

Referring now particularly to Fig. 1, I have shown therein a wall made up of an outer row of relatively wide blocks, such as eight inch blocks, and an inner row of relatively narrow blocks, such as four inch blocks. This wall is composed of blocks F which are of the ordinary rectangular shape. The blocks A are also rectangular, and are similar in form to the blocks F and are laid 60 vertically. Above the blocks A are the mitered blocks B and C, these blocks being so arranged that they cover the voids of the blocks A while fitting together in a manner to conceal their own voids. Above the blocks 70 B and C is another corner block A, while above the second block A are other blocks B and C.

The construction described permits the laying of the majority of the blocks horizontally. In the ordinary manner of completing piers or walls, where the blocks are laid vertically, the mortar will fall down into the voids, filling up the voids, and at the same time weakening the construction, 75 since relatively little mortar will remain on the narrow edges. My form of construction provides a broad base for the mortar and it also tends to lock the various courses, thereby providing a stable as well as a 80 sightly construction.

In Fig. 3 I have shown the manner of constructing a pier or column. In this figure, as in Fig. 1, the courses have mitered blocks B and C lining with vertically arranged corner blocks A. The construction is especially desirable in columns and piers, since these have to bear heavy loads and are far more stable when the blocks are laid 90 horizontally, for the reasons stated above. 95

In Fig. 4 I have shown a means for constructing a window jamb. In this figure the blocks F are ordinary rectangular blocks. The block D is similar to the block B of the wall shown in Fig. 1. The block E, however, is mitered, so that when assembled with the block D it will complete the block and effectively close the end of the same, so as to hide the voids of the block D.

In Fig. 1 I have shown a wall of two rows 105 of blocks. In Fig. 3 I have shown a pier whose walls have a thickness of only one block, but it is obvious that the walls may

be of any desired thickness, without departing from the spirit of the invention.

The material of which the block is composed forms no essential part of the invention, since the invention contemplates the use of any hollow block mitered in the manner described. The mitered blocks are made from the same dies as the blocks of ordinary size, and they are cut while the material 5 is in a plastic condition, if the block is of terra cotta or the like. Cement blocks, of course, may be molded and then allowed to set in molds which form the mitered blocks.

It will be understood also that while I 15 have shown the blocks as mitered at an angle of forty-five degrees, they may be mitered at different angles, or the blocks may be of different lengths than those shown in the drawings, without departing from the 20 invention.

I claim:—

1. A hollow wall construction comprising a series of hollow blocks arranged in courses, the majority of said hollow blocks being laid 25 horizontally, certain of the blocks being arranged in vertical position to form corners of certain courses, and mitered blocks disposed at the corners of the remaining courses adjacent to the vertically disposed 30 blocks.

2. In a hollow wall construction, a plurality of courses of hollow blocks, the majority of said hollow blocks being laid horizontally, a series of hollow blocks disposed 35 at the corner of the wall in vertical position, a pair of mitered blocks fitting together

along their mitered edges, said mitered blocks being disposed between the adjacent vertical blocks.

3. A hollow wall construction comprising 40 a series of courses of horizontally laid hollow blocks, the blocks of certain courses having a corner block consisting of one of the horizontal blocks laid vertically, other adjacent courses consisting of hollow blocks 45 laid horizontally, the corners of said last named courses comprising a pair of mitered hollow blocks placed together along their mitered edges and arranged to engage the ends of the vertically disposed blocks in adjacent courses, so as to cover the voids in the 50 vertically disposed blocks.

4. A hollow wall construction consisting of a plurality of courses of horizontally laid hollow blocks, the voids of said blocks running in a horizontal direction, the blocks of certain courses having a corner block consisting of one of the hollow blocks laid vertically, other adjacent courses consisting of hollow blocks laid horizontally, the corners of said last named courses comprising a pair of mitered hollow blocks having voids registering with the voids of said horizontally laid blocks, said mitered blocks being placed together along their mitered edges to provide 60 continuous air spaces, the upper and lower edges of the mitered blocks being arranged to engage the ends of the vertically disposed blocks in adjacent courses so as to cover the voids in the vertically disposed 65 blocks.

FREDERICK HEATH.
